UNITED STATES PATENT OFFICE.

GEORGE J. CUZNER, OF MIAMISBURG, OHIO, ASSIGNOR TO THE HOOVER & GAMBLE COMPANY, OF SAME PLACE.

SPINNING-MACHINE.

SPECIFICATION forming part of Letters Patent No. 681,628, dated August 27, 1901.

Application filed January 21, 1901. Serial No. 44,055. (No model.)

To all whom it may concern:

Be it known that I, GEORGE J. CUZNER, a citizen of the United States, residing at Mi-
5 amisburg, in the county of Montgomery and
State of Ohio, have invented certain new and
useful Improvements in Spinning-Machines,
of which the following is a specification.

My invention relates to an improvement in
spinning-machines, the object being to sim-
10 plify the mechanism, to cheapen the cost, and
to increase the efficiency.

In the spinning-machine of the old art em-
ploying a rotary flier, a capstan thereon, and
15 a receiving-bobbin, each taking motion from
a separate driving device, it is obvious that
a discrepancy in the feed of any one or more
of these separate drives throws out of balance
or proper time movement the operations of
20 the remaining parts. For instance, lost ac-
tion, belt-slippage, or an overspeeding of the
capstan, will produce an over or an under
twisting of the string for which no compen-
sation is made in the other parts, and con-
25 sequently the function of both the flier and
bobbin would be deranged. The preferred
form of my invention entirely obviates all
these difficulties, and the parts may be adapted
to be readily applied to an ordinary spinner.

The features of my invention will be more
30 fully set forth in the description of the ac-
companying drawings, forming a part of this
specification, in which—

Figure 1 is a sectional elevation of my im-
provement. Fig. 2 is a side elevation of my
35 improvement. Fig. 3 is a front plan view of
the revolving friction-disk. Fig. 4 is a plan
view of the stationary friction-plate.

A represents the ordinary flier journaled
on the ordinary frame.

40 B represents the central spindle passing
through the head 2 of the flier. Journaled
upon this spindle is the bobbin C, fixed to
the bobbin-sleeve C', which passes through
the head 2 of the flier.

45 D represents a gear-sleeve journaled on the
bobbin-sleeve outside of the head 2 of the
flier and attached thereto for driving the flier.
To this sleeve is cast or otherwise fixed the
driving-gear D'.

50 E represents a bearing device suitably based
upon the machine-frame, in which the outer

end of the gear-sleeve D is journaled. One
face of this bearing device is formed into a
friction-disk E', which will be later described.
(See Fig. 4.)

55

Turning to the other head 1 of the flier F
represents a funnel-shaped tube upon which
this head of the flier is journaled, the funnel
portion of the tube opening toward the fiber-
feeding mechanism. (Not necessary to be
60 shown.) To this journal-tube, just inside of
the capstan-head 1, is fixed a gear 3. The
capstan has the usual grooved rollers G H
fixed to the gears 4 5, respectively, which are
65 journaled on the flier-head 1, with the said
gear-wheels 4 5 respectively intermeshed
with the intermediate fixed gear 3, from which
they are driven when the flier is rotated.

The brake mechanism for the bobbin-sleeve
70 consists of the following parts.

Secured to the friction-disk E' is a smaller
disk I, by means of truss-rods a b c. These
form the stationary heads between which the
rotary friction-disk J is adjustably secured.
This friction-disk J is feathered and splined
75 to the bobbin-sleeve, so as to turn therewith
and so as to allow the bobbin-sleeve to be re-
ciprocated therein.

d represents a friction-washer of suitable
material interposed between the stationary
80 and rotary friction-disks.

K represents a coil-spring, one end of which
bears against an adjusting-collar L, screw-
threaded into the disk I. The other end of
said spring bears against the rotary friction-
disk J, pressing it normally into contact with
85 the opposing friction-disk. It will be seen that
by means of this adjusting-collar the degree
of friction can be most delicately adjusted,
and hence the tension between the flier and
90 bobbin can thus be positively controlled.

h represent aerating-tubes through the
face of the rotary disk to supply air to the con-
tacting frictional surfaces. The outer ends
of the tubes are preferably funnel-shaped,
95 by means of which air-currents are created by
the revolution of the disk and constantly sup-
plied to the frictional surfaces. It is obvi-
ous that in the high-speed mechanism
such as above described a means for keep-
100 ing the temperature approximately down to
safety is of great practical value. The sta-

tionary disk E' has orifices *i i* to supply air to the contacting frictional surfaces.

The mechanism for reciprocating the bobbin is of usual form (shown in Fig. 2) consisting of the collar M, arm N, worm-shaft O, and gears *x y z*, worm-shaft Q, and the gears *u v* at the end of said worm-shaft Q.

Mode of operation: The driving means is shown, preferably, in the form of a gear, which 10 may be positively driven by a counter-shaft in the lower part of the machine-frame. It is obvious that a belt-pulley might be employed in lieu thereof, or other equivalent power-transmitting devices may be employed. 15 As the flier is turned by this gear to which it is fixed it revolves the capstan-gears G H around the fixed gear 3, the gears being so proportioned relatively as to give the proper speed to the capstan. The string from the 20 capstan is fed in the usual manner over the rollers *e f* on the bars of the flier, passing thence around the bobbin. The bobbin is therefore rotated by this string; but the rate of retarded revolution is determined by the 25 friction mechanism of the bobbin-sleeve, which is adjusted to suit the nature of the work. It will thus be seen that the capstan and the bobbin are both independently journaled within the flier and receive their speed 30 therefrom, so that the relative movements of these separate parts are invariable. The capstan can operate on the string no faster and no slower than it is fed by the flier, and the speed of the bobbin is likewise in a direct 35 and invariable ratio to the speed of the flier.

The advantages of this invention may be partially realized by independently driving the capstan as well as the flier and leaving the bobbin independently journaled, though 40 it is obvious that a single drive is the simplest as well as the best. In short, by means of a single drive the highest possible efficiency of the spinning-machine is realized, because of the invariable relative speed of 45 the several parts.

It is obvious that in addition to the simplicity, construction, and operation of spinning-machines by my invention, owing to the perfect and invariable performance of 50 the representative functions of the several parts, the quantity of the output is greatly increased; but of even more importance is the improved character of the result in quality. It is evident that in the old spinning-machines even the slightest variation, not enough 55 to actually break the twine, causes an unevenness and non-uniformity of string which greatly damages its commercial value and utility. With my invention an unbroken 60 string of practical uniformity in texture and quality is produced.

Having described my invention, I claim—

1. In a fiber-spinning machine, a revolving

flier, means for driving the same, a capstan journaled on the flier, power-transmitting devices between the capstan and flier, an independently-journaled bobbin-shaft, a brake mechanism for said shaft, and means for reciprocating said shaft, whereby the relative rotations of the flier, capstan and bobbin-shaft are maintained invariable, substantially as specified. 65 70

2. In a spinning-machine, a flier provided with two heads, a bobbin-shaft independently journaled in one of said heads, means for retarding the rotation of said shaft, means for reciprocating said shaft, a capstan journaled on the other flier-head, power-transmitting devices between said flier and capstan, and a single driving mechanism, substantially as 80 specified. 85

3. In a spinning-machine, a flier provided with two heads, a driving device attached to one of said heads, a bobbin-shaft independently journaled in one of said heads, a retarding mechanism for said shaft, a funnel-shaped receiver upon which the other head of the flier is journaled, a capstan journaled inside of said head, and power-transmitting devices between said flier and capstan, substantially as specified. 90

4. In a spinning-machine, a brake mechanism for the bobbin-shaft consisting of two stationary disks trussed together on said shaft, one being a friction-disk, a rotary disk fixed 95 to turn with said shaft between said stationary disks, a spring interposed between one of said stationary disks and the rotary disk, adapted to force the rotary disk normally against the stationary friction-disk, and 100 means for adjusting the tension of said spring, substantially as specified.

5. In a spinning-machine, a brake mechanism for the bobbin-shaft consisting of two stationary disks trussed together on said shaft, 105 a disk fixed to turn with and slide on said shaft between said stationary disks, a spring interposed between the rotary disk and one of said stationary disks, a sleeve screw-threaded into the stationary disk against which the spring abuts, adapted to regulate the tension, substantially as specified.

6. In a spinning-machine, in combination with a brake mechanism for the bobbin-shaft, a stationary disk and a rotary disk normally 115 in contact therewith, and aerating ducts formed through the rotary disk adapted to conduct currents of air upon the contacting frictional surfaces when in motion, substantially as specified. 120

In testimony whereof I have hereunto set my hand.

GEORGE J. CUZNER.
